UNITED STATES PATENT OFFICE

2,506,228

COUNTERBALANCE FOR GLASSWARE
WASHING MACHINES

Anders R. Lofstrand, Sr., Silver Spring, Md.

Original application August 19, 1943, Serial No.
499,271. Divided and this application August
16, 1946, Serial No. 690,941

1 Claim. (Cl. 248—123)

1

This invention relates to improvements in glassware washing machines and is an improvement over the washing machines embodied in prior Patents Nos. 1,992,920, issued February 26, 1935, and 2,052,835, issued September 1, 1936, and is a division of my copending application, Serial Number 499,271, filed August 19, 1943, now Patent No. 2,480,150, issued August 30, 1949.

An object of this invention is to provide an improved glassware washing machine which is designed particularly for use in washing tumblers which are positioned in a wire basket.

Another object of this invention is to provide a machine of this kind including a vertically movable elevator adapted to support the tumblers or glassware, the elevator being substantially balanced so as to eliminate any undue weight in the operation of the machine.

Still another object of this invention is to provide an improved means in the form of a compensating structure for compensating or equalizing the tension on the elevator, and the operating lever as the lever is rocked to lower the elevator into the desired washing compartment or to raise the elevator from the compartment.

A further object of this invention is to provide a compensating structure for use with the elevator of a dishwashing machine of the kind described which includes a spring, a flexible cord connected between the elevator and the spring and a differential pulley about which the cord is trained for varying the spring tension disproportionately to the elevator travel.

With the above and other objects in view, my invention consists in the arrangement, combination and details of construction disclosed in the drawings and specification, and then more particularly pointed out in the appended claim.

In the drawings, wherein similar reference characters designate similar parts throughout the respective views,

Figure 1 is a sectional view, partly broken away, of the elevator counterbalance constructed according to an embodiment of my invention,

Figure 2 is a detail sectional view of the lower end of the counterbalance, and

Figure 3 is a horizontal section taken on the line 3—3 of Figure 1.

Referring to the drawings, the numeral 51 designates generally an elevator structure movably supported relative to a horizontally shiftable carrier 26 which in turn is supported above a tub 15 by rollers 35 engaging in the tracking 28. The elevator structure 51 includes a basket supporting frame 52 which is secured to the lower end of a

depending bar 53. The supporting frame 52 is an open frame being formed with a basket seat 54, and a vertically disposed rear flange 55 to which the lower end of the supporting bar 53 is secured. The frame 52 is of a size to loosely engage within the opening 40 in the top of the tub 15 and is adapted to have positioned thereon, a wire basket 56 within which tumblers 57, disposed in an inverted position, are adapted to engage. The supporting bar 53 is secured at its upper end by fastening members 58 to a vertically disposed block 59. The block 59 forms part of a vertically movable carriage 60. The carriage 60 includes an arcuate plate 61, having opposed pairs of rollers 62 secured to the open side thereof. The rollers 62 movably engage in vertically disposed grooves 63, formed in the vertical elevator supporting post 64. The supporting post 64 is secured at its lower end to a rearwardly projecting boss 65 by means of set screws 66. The supporting post or standard 64 has mounted on the upper end thereof of a cap 67 which is secured to the upper end of the standard or post 64 by means of a set screw 68. A forwardly projecting plate 69 is formed integral with or secured to the cap 67 and the plate 69 has formed integral therewith an L-shaped bracket 70. The bracket 70 includes a lower horizontal leg 71 which is downwardly offset by means of a connecting part 72 from the plate 69. A vertically disposed leg 73 extends upwardly from the forward end of the horizontal leg 71, and is braced by means of a web 74. The block 59, at the upper end thereof, has formed integral therewith an upwardly extending ear or lug 75 which constitutes a clamping jaw and a clamping plate 76 is adapted to confront the lug or clamping member 75, being secured in clamping position by means of fastening members 77 so as to tightly secure one end of a flexible cable 78.

The cable 78 is trained over a spirally grooved pulley 79 which is rotatably mounted on the shaft 80. The shaft 80 is disposed between a pair of upwardly extending ears 81 secured to or formed integral with the cap 67. The cable 78 extends through an opening 82 in the plate 69 and also through an opening 83 in the cap 67. The cable 78 is extended downwardly into the interior of the post or standard 64 and has secured to the lower end thereof a cup-shaped slide member 84. The slide member 84 is constantly urged downwardly by means of a spring 85, which has the lower end thereof engaging against the slide member 84 and the upper end bearing against the inner side of the cap 67. The cable 78 extends downwardly through the interior of the

spring 85. As the carriage 61, which also includes the block 59, is moved downwardly along the post or standard 64, the slide 84 will be pulled upwardly, thereby compressing the spring 85, this spring constituting a balancing spring for substantially balancing the carriage 61 along the length of the supporting post 64.

A brush carrier 86, slidably mounted on the carriage 59, 61 and the lever structure 92, are adapted to be held in a depressed position by bar 110 engaging the latch plate or keeper 123, and further downward movement of the handle 90 forces the elevator 51 downwardly.

The movement of the cable 78 along the spiral groove 79 is from the large end or larger diameter of the pulley to the small end or smaller diameter as the elevator 51 is being lowered in such a manner that the change of force on the spring 85 will be lowered with further downward travel of the elevator 51, in other words, the rate of change of spring tension decreases with additional downward movement of the elevator 51 thereby providing a nearly constant force on the cable 78 throughout the elevator travel and the counterbalancing effect of the spring is practically constant irrespective of the relative position of the elevator with respect to the support 64.

I do not mean to confine myself to the exact details of construction herein disclosed but claim all variations falling within the purview of the appended claim.

What I desire to claim is:

In a glassware washing machine, a counterbalance structure comprising a vertical tubular support, a slide member movable on said support, a second slide member within said support, a spring engaging between said second slide member and one end of said tubular support constantly urging said second slide member downwardly, a spiral grooved pulley supported by and over the end of said tubular support, and a flexible member between said slide members trained over said pulley, that portion of the flexible member between said pulley and said first slide member terminally engaging a larger diameter of said pulley at a greater distance from the center thereof than that portion between the pulley and said second slide member engaging a smaller diameter of said pulley for progressively decreasing the increase of spring tension occasioned by the lowering of said first slide member on said support.
